UNITED STATES PATENT OFFICE.

JOHN WICKS, OF OAK PARK, ILLINOIS, ASSIGNOR, BY MESNE ASSIGNMENTS, TO AUTOMATIC ELECTRIC INC., OF CHICAGO, ILLINOIS, A CORPORATION OF DELAWARE.

AUTOMATIC TELEPHONE SYSTEM.

Application filed May 19, 1924, Serial No. 714,240. Renewed May 11, 1928.

The present invention relates to automatic telephone systems in general, but is concerned more particularly with automatic telephone systems in which talking battery is supplied from a trunking switch (selector) rather than from a final switch (connector). As to a number of its features, this case may be considered an improvement on my co-pending application, Serial No. 680,596, filed December 14, 1923.

According to one feature of this invention, the first selector repeater supplies battery during the impulsing period to the line relay of the switch to which it repeats impulses, so as to simplify the switch-over operation which takes place after the dialing is completed and before the conversation can start.

According to another feature of the invention, arrangements have been made whereby a call originated in a so-called "inverted" office, i. e., an office in which the first selector repeater feeds talking battery both ways, may be completed through a special incoming selector repeater to a called line terminating in an ordinary two-wire office in which the connector switch feeds talking battery both ways.

According to another feature of the invention, novel circuit arrangements have been provided to enable a first selector repeater to switch straight through on certain calls like an ordinary two-wire selector, the repeating apparatus being cut out of the circuit. According to still another feature of the invention, special arrangements have been made whereby a system embodying the features of the present invention is made to cooperate with a director system of the general type disclosed in the co-pending application of Richardson et al., Serial No. 547,866, filed March 29, 1922, but more particularly of the type disclosed in the co-pending application of Nelson, Serial No. 573,175, filed July 8, 1922.

There are several other features and objects of the invention which need not be dwelled upon here, as they can be best understood from a perusal of the detailed description which is to follow.

Reference may now be had to the accompanying drawings comprising Figs. 1-11, inclusive, which show, by means of the usual circuit diagrams, a sufficient amount of apparatus employed in a multi-office tele-

phone system embodying the features of the invention to enable the invention to be understood and its utility appreciated.

As the invention is of such scope as to be applicable to a number of situations which may not be found in a single multi-office telephone exchange area, the disclosure in the drawings is not limited to any one multi-office system. Accordingly, Figs. 1-7, inclusive when taken together, illustrate a certain amount of apparatus in a multi-office system composed of two or more so-called "inverted" offices and one or more offices of the ordinary or non-inverted type; Fig. 8, taken in connection with Figs. 2-5, inclusive, discloses a certain amount of equipment in a multi-office system in which all offices are of the inverted type; and Figs. 9 and 10, when taken in connection with Figs. 2-7, inclusive, disclose a certain amount of equipment in a mixed multi-office system in which directors are employed to register and retransmit the telephone numbers so as to direct the calls according to the most economical trunking arrangements. Fig. 11 is a layout drawing which shows how Figs. 1-7, inclusive, should be placed together in order to be understood best.

Considering first Figs. 1-7, inclusive, Fig. 1 shows the party line of substations A and A' terminating at the exchange in the rotary line switch LS. The rotary line switch LS has access in common with other line switches in the same group to a number of first selector repeaters, of which only one is shown.

The first selector repeater of Fig. 1 may be used to establish a connection through the incoming selector repeater, Fig. 2, in an inverted office, the intermediate selector, Fig. 3, and the connector, Fig. 4 to the line of substation B. This first selector repeater may be used also to extend the connection through the incoming selector repeater of Fig. 6 in an office of the ordinary two-wire type, the two wire selector S, Fig. 7, and the connector C to the line of substation B' and may also be used in connection with the intermediate selector of Fig. 5, which is denoted by a dotted rectangle, and the reverting call switch and the common reverting call ringing equipment when a connection is desired with another subscriber on the same line as the calling subscriber. It will also be understood that the first selec-

tor repeater may be used to extend a connection to a subscriber in the local office through two intermediate selectors and a connector, in which case talking battery is supplied to the calling line and called line both by the first selector repeater.

The incoming selector repeater of Fig. 2 is reached over the two-way trunk line TL when the latter is seized by a first selector repeater, such as the one shown in Fig. 1. There is a duplicate incoming selector repeater on the left hand end of the trunk line TL in the office local to Fig. 1, which is used on calls coming back the other way when the trunk line TL is seized by a first selector repeater local to the office in which the incoming selector repeater of Fig. 2 is located.

In order to enable the invention to be understood best, a detailed description of the operation of the apparatus shown will be given. First it will be assumed that the subscriber at substation A, Fig. 1, desiring to converse with the subscriber at substation B, Fig. 4, removes his receiver.

When the receiver is removed at substation A, line relay 6 energizes over conductors 2 and 3 and places ground on private normal conductor 4 at armature 11, thereby making the calling line busy to the connectors having access to it and closing a circuit through switching relay 5 and stepping magnet 7 in series. Line relay 6 also connects test wiper 14 to the junction of switching relay 5 and stepping magnet 7 at armature 12. However, in case the trunk terminating in the bank contacts upon which the wipers of the line switch are standing is idle, this latter operation does not have any particular utility and switching relay 5 energizes immediately, seizing the trunk. On the other hand, if the said trunk is busy, switching relay 5 is short circuited by the ground potential encountered on the busy test contact by test wiper 14 and does not energize. In this case, stepping magnet 7, which interrupts its own circuit, is operated through test wiper 14 and advances the wipers 13-15, inclusive, step by step in search of an idle trunk. When an idle trunk is reached, which trunk, it will be assumed, is the one comprising conductors 17-19, inclusive, switching relay 5, being no longer short circuited, energizes in series with stepping magnet 7. Stepping magnet 7, however, does not energize at this time, on account of the high resistance of switching relay 5. Upon energizing, switching relay 5 opens the test circuit and prepares the holding circuit at armature 9 and at armatures 8 and 10 disconnects line conductors 2 and 3 from the winding of line relay 6 and ground, respectively, and extends them by way of wipers 13 and 15, the bank contacts upon which they are standing, conductors 17 and 19, and the normally closed contacts controlled by armatures 54

and 57 to the upper and lower windings, respectively, of the double wound line relay 32 of the first selector repeater.

Line relay 32 now energizes over the calling line and closes its repeating contacts at 79 armature 58 whereupon relays 39 and 40 energize in series over the following circuit: from ground by way of relay 39, resting contact and armature 57, normally closed contacts controlled by armature 79, armature 54 and its resting contact, working contact and armature 58, and relay 40 to battery. Relays 39 and 40 thereupon energize and the latter opens a point in the circuit of relay 35 so as to prevent the latter from operating upon the energization of switching relay 41, which is to take place subsequently. As a further result of the energization of line relay 32, it closes at armature 59 a circuit for release relay 33. Release relay 33 85 thereupon energizes; opens a point in the circuit of release magnet 42 and prepares a circuit for vertical magnet 48 at armature 62; and at armature 61 places ground upon release trunk conductor 18 through the normally closed contacts controlled by armature 68, thereby establishing the usual holding circuit for switching relay 5 of the line switch LS before the slow acting line relay 6 has had time to deenergize.

In the first selector repeater, as a further result of the energization of release relay 33, it places ground upon conductor 51 at armature 60 through the low resistance lower winding of the marginal relay 31, thereby closing a circuit through the normally closed contacts controlled by armature 84 for the slow acting relay 34. Relay 34 thereupon energizes, but relay 31 does not energize on account of the relatively high resistance of relay 34. Upon energizing, relay 34 connects the upper talking condenser at armature 63 to the tone lead 25 through the normally closed contacts controlled by the eleventh rotary step spring 47 and 110 through off normal spring 44 and its resting contact. Accordingly, dial tone from the source 24 is transmitted back to the calling subscriber to inform him that he may now proceed to call the desired number.

When the calling subscriber manipulates his calling device in accordance with the first digit in the desired number, the circuit of line relay 32 is opened a corresponding number of times. Each time its circuit is opened, line relay 32 deenergizes momentarily and closes at armature 59 a circuit through armature 62 and its working contact and armature 84 and its resting contact for vertical magnet 48. By the operation of 125 vertical magnet 48, the wipers 86-88, inclusive, are raised step by step and come to rest opposite the desired level of bank contacts. Relay 37 is energized in multiple with vertical magnet 48 through the resting 130

contact and armature 83 and, being slow acting, maintains its armature attracted throughout the vertical movement. Upon energizing, relay 37 closes at armature 72 5 a circuit through armature 82 and its resting contact and off normal contacts 45 for stepping relay 38. Stepping relay 38 thereupon energizes and completes at armature 74 a locking circuit for itself through the 10 interrupter contacts 50 and the off normal contacts 45 and at armature 75 prepares a circuit for rotary magnet 49. It will be noted that upon the operation of the off normal springs, which occurs at the first vertical 15 cal step, spring 44 disconnects the upper talking condenser from ground through the dial tone conductor and connects it to the lower winding of the line relay. This bridges the upper talking condenser right 20 across the line. This is done so as to permit the line relay 32 to respond more readily to the interruptions produced in its circuit.

At the end of the vertical movement, relay 37 deenergizes and completes the circuit of 25 rotary magnet 49 at the normally closed contacts controlled by armature 72. Rotary magnet 49 thereupon energizes and advances the wipers 86-88, inclusive, into engagement with the first set of bank contacts in the selected level and, near the end of its stroke, 30 opens the locking circuit of stepping relay 38 at the interrupter contacts 50. Stepping relay 38 thereupon deenergizes and opens the circuit of rotary magnet 49 at armature 35 75, whereupon rotary magnet 49 deenergizes also and closes its interrupter contacts 50 again.

In case the trunk terminating in the first set of bank contacts is idle, switching relay 40 41 now energizes and seizes the trunk. Assuming the trunk to be busy, however, switching relay 41 is short circuited by the ground potential encountered upon the busy test contact by test wiper 87 and does not 45 energize. Stepping relay 38 energizes through test wiper 87 and closes the circuit of rotary magnet 49 again at armature 75, whereupon rotary magnet 49 energizes again and advances the wipers into engagement 50 with the second set of bank contacts.

This alternate operation of stepping relay 38 and rotary magnet 49 continues as described until an idle trunk is reached, which trunk, it will be assumed, is the one comprising conductors 92-94, inclusive. When such idle trunk is reached, switching relay 55 41, being no longer short circuited, energizes in series with stepping relay 38 over the following circuit: from ground by way of the grounded conductor 51, relay 41, the 60 eleventh rotary step contacts 46, interrupter contacts 50, off normal contacts 45 and stepping relay 38 to battery. Stepping relay 38, however, does not energize over this circuit on account of the high resistance of 65 switching relay 41. Upon energizing, switching relay 41 opens the test circuit and places ground upon test wiper 87 at armature 80, thereby making the seized trunk busy immediately to the other switches having access to it; disconnects armature 72 of relay 37 at armature 82 so as to prevent a further operation of stepping relay 38; prepares a circuit for relay 35 at armature 81; disconnects the operating conductor from vertical 70 magnet 48 at armature 84 and extends it to relay 34 at the same time disconnecting the latter from the grounded conductor 51; and at armatures 79 and 85 connects up the wipers 86 and 88, at the same time opening the initial circuit of relays 39 and 40 at the normally closed contacts controlled by armature 79. Relays 39 and 40, however, do not deenergize at this time, however, but are held up over the trunk line TL and through the 75 two windings of relay 107 of the incoming selector repeater, Fig. 2, in series, relay 107 being bridged across the trunk line TL through armatures 121 and 122 of the cut-off relay 101 and through the normally 80 closed contacts controlled by armature 140 of relay 109 and the off normal contacts 113. Relay 107 now energizes over the trunk line TL and in series with the relays 39 and 40 and closes at armature 134 a circuit for the repeating relay 102 through the resistance 117. Relay 102 thereupon energizes and closes at armature 124 a circuit for release relay 103 and closes at armature 123 a circuit through relay 109 as follows: from ground by way of the upper winding of relay 109, normally closed contacts controlled by armature 143, armature 123, upper winding of relay 105, and the upper winding of relay 106 to battery. Relays 109, 105, 106 energize over this circuit and relay 109 locks itself at armature 139 to ground through armature 129 and its working contact of relay 105; shunts the upper talking condenser across the talking circuit at armature 137 and consequently around the line relay 107 so as to improve the impulsing circuit; short circuits the resistance 117 at armature 138 so as to furnish more current to the repeating relay 102; connects the upper winding of line relay 107 directly across the line at armature 140 at the same time disconnecting the lower winding of the relay; prepares a locking circuit for stepping relay 108 at armature 141, thereby grounding one terminal of the lower talking condenser; and at armature 142 disconnects the left hand terminal of the now grounded lower talking condenser from the lower talking conductor and connects it through the low resistance 119 to the repeating armature 134 of relay 107. This is done so as to improve the response of the relay 102 to the interruptions in its circuit produced at armature 134.

As a further result of the energization of the repeating relay 102, it closes at armature 124 a circuit for release relay 103. Release relay 103 thereupon energizes; prepares the operating circuit at armature 127; grounds conductor 171 at armature 126; and at armature 125 disconnects the cut-off relay 101 and grounds the local test conductor, thereby guarding the trunk line TL from seizure at this end also.

When the calling subscriber manipulates his calling device in accordance with the second digit in the desired number, line relay 32 of the first selector repeater, Fig. 1, is deenergized a corresponding number of times and, upon each deenergization, interrupts the battery bridge across the wipers 86 and 88 at armature 58. Upon the first interruption of this bridge, relays 39 and 40 deenergize and relay 40 attempts to close a circuit at armature 73 and through armature 81 and its working contact for relay 35, but ground is removed from this circuit at armature 64 of relay 34 which energizes over the operating circuit and through armature 84 and its working contact responsive to the first deenergization of line relay 32. Relay 34 also short circuits relay 39 at armature 64 so as to improve the impulsing circuit over which the line relay of the incoming selector repeater is operated. Relay 34 also shunts the upper talking condenser across the incoming trunk conductors at armature 63 and through the normally closed contacts controlled by the cam spring 47 and off normal spring 44 and its upper contact so as to improve the impulsing characteristics of the trunk line.

At the end of the series of deenergizations of line relay 32, relay 40 energizes and remains energized and the slow acting relay 34 deenergizes after an interval, restoring the circuits to their previous condition.

In the incoming selector repeater, Fig. 2, line relay 107 deenergizes each time its circuit is opened at armature 58 of line relay 32, Fig. 1. Upon each deenergization, relay 107 opens the circuit of the repeating relay 102 at armature 134. Upon its first deenergization, relay 102 opens the previously traced circuit through the upper windings of relays 105, 106, and 109. Relays 105 and 106 deenergize but relay 109 does not deenergize responsive to the opening of the circuit through its upper winding because it is now locked up through its lower winding to ground supplied by relay 105. Before relay 105 has had time to fall back, the locking circuit of relay 109 is taken over by relay 104 at the normally open contacts controlled by armature 128, relay 104 being energized through armature 124 of relay 102 and its resting contact and armature 127 and its working contact. Relay 104, being slow acting, remains energized throughout the

series of impulses transmitted to it by relay 102. As a further result of each deenergization of relay 102, vertical magnet 120 is energized in multiple with relay 104 and through armature 146 and its resting contact. By the operation of vertical magnet 120, the wipers 148-150, inclusive, are raised step by step and come to rest opposite the desired level of bank contacts. Upon the closure of the off normal contacts 114, which occurs upon the first vertical step of the switch, a circuit is closed for stepping relay 108 as follows: from ground by way of the grounded conductor 171, working contact and armature 128 of the now energized slow acting relay 104, armature 145 and its resting contact, off normal contacts 114, and relay 108 to battery. Upon energizing, relay 108 prepares a circuit for rotary magnet 118 at armature 135 and at armature 136 closes a locking circuit for itself as follows: from ground by way of the working contact and armature 141 of relay 109, armature 147 and its resting contact, armature 146 and its working contact, interrupter contacts of rotary magnet 118, off normal contacts 114, and relay 108 to battery.

At the end of the series of deenergizations of relay 102, relays 105 and 106 energize through armature 123 and remain energized and relay 105 maintains the initial locking circuit of relay 109 closed at armature 129. A moment later, the slow acting relay 104 deenergizes and opens the temporary locking circuit of relay 109 at the normally open contacts controlled by armature 128, leaving the lower winding of the relay energized over the initial locking circuit. Relay 104 also completes the circuit of the rotary magnet 118 at the normally closed contacts controlled by armature 128. Accordingly, the incoming selector repeater hunts for and finds an idle trunk in the same manner as the first selector repeater, which trunk, it will be assumed, is the trunk extending to the intermediate selector, Fig. 3. When this occurs, switching relay 110 energizes over the following circuit: from ground by way of the grounded conductor 171, switching relay 110, the interrupter contacts of the rotary magnet 118, off normal contacts 114, and stepping relay 108 to battery. Upon energizing, relay 110 opens the test circuit and grounds the test wiper 149 at armature 144; disconnects vertical magnet 120 at armature 146; disconnects armature 128 of relay 104 at armature 145 so as to prevent relay 104 from again operating the stepping relay 108; and at armatures 143 and 147 connects up the line wipers 148 and 150, at the same time removing relay 109 from the initial circuit of the upper windings of relays 105 and 106 at the normally closed contacts controlled by armature 143. Relays 105 and 106

106 are now maintained energized over conductors 161 and 163 of the intermediate selector, Fig. 3, line relay 201 being bridged across conductors 161 and 163 at the intermediate selector through the normally closed contacts controlled by armatures 228 and 232 and conductor 163 being grounded in the incoming selector repeater through wiper 150 at armature 141 of relay 109.

10 In the intermediate selector, Fig. 3, line relay 201 now energizes and closes a circuit from the grounded release trunk conductor 162 for the combined release and change-over relay 203 at armature 221 in series with the resistance 202. Relay 203 thereupon energizes; closes a locking circuit for itself at armature 223, prepares a circuit for stepping relay 204 at armature 224, at the same time opening a point in the circuit of rotary magnet 210; and at armature 225 prepares a circuit for vertical magnet 209 and opens a point in the circuit of release magnet 206.

When the calling subscriber operates his calling device in accordance with the third digit in the desired number, the interruptions produced in the circuit of the line relay of the first selector repeater are repeated to the incoming selector repeater and are again repeated in the circuit of line relay 201 of the intermediate selector at armature 123 of relay 102 of the incoming selector repeater. Accordingly, line relay 201 deenergizes momentarily for each interruption and closes at armature 223 a circuit through armature 225 and its working contact for vertical magnet 209. By the operation of vertical magnet 209, the wipers 233-235, inclusive, are raised step by step and come to rest opposite the desired level of bank contacts. Upon the closure of the off normal contacts 205, a circuit is completed for stepping relay 204 which includes the working contact and armature 204 and contacts 207 of release magnet 206. Relay 204, upon energizing, prepares a circuit for rotary magnet 210 at armature 226 and at armature 227 closes a locking circuit for itself from ground by way of the resting contact and armature 231 and through the interrupter contacts 211 of the rotary magnet 210 and off normal contacts 212.

As a further result of the operation of the off normal springs upon the first vertical step of the switch, the off normal contacts 214 close and prepare a direct circuit for the resistance 202. Accordingly, upon each subsequent energization of relay 201, relay 203 is short circuited at armature 222. However, relay 203 will not deenergize immediately responsive to being short circuited, owing to the fact that a short circuited relay is slow acting, as is well known. Accordingly, relay 203 remains energized

throughout the series of deenergizations of line relay 201.

At the end of the vertical movement, line relay 201 comes to rest in an energized condition and relay 203, being short circuited, deenergizes and completes the circuit of the rotary magnet 210. Rotary magnet 210 thereupon energizes and advances the wipers 233-235, inclusive, into engagement with the first set of bank contacts, at the same time opening the circuit of stepping relay 204 at contacts 211. The remaining part of the trunk selecting operation is the same as has been described hereinbefore and the intermediate selector selects an idle trunk, which trunk, it will be assumed, is the one comprising conductors 236-238, inclusive. When this occurs, switching relay 205 energizes over the following circuit: from ground by way of the grounded release trunk conductor 162, switching relay 205, interrupter contacts 211, off normal contacts 212, and stepping relay 204 to battery. Upon energizing, switching relay 205 opens the test circuit and grounds test wiper 234 at armature 229; disconnects ground from armature 222 of line relay 201 at armature 231; at armature 230 disconnects the deenergized relay 203 from the release trunk conductor 162; and at armatures 228 and 232 connects up the line wipers 233 and 235, at the same time disconnecting line relay 201. In the connector, Fig. 4, responsive to ground being placed upon the release trunk conductor 237 by the intermediate selector, Fig. 3, a circuit is closed through off normal contacts 310 for the lower winding of the combined change-over and ring cut-off relay 303. Relay 303 thereupon energizes and disconnects the operating conductor 315 from the rotary magnet 311 and connects it to vertical magnet 312 at armature 329 and at armature 327 closes a point in the circuit of release relay 302. Also line relay 301, which is bridged across conductors 236 and 238 through the resting contact and armature 338 and off normal contacts 309 and the normally closed contacts controlled by armature 325, energizes over conductors 236 and 238 and in series with the upper windings of relays 105 and 106 of the incoming selector repeater, Fig. 2. Upon energizing, relay 301 completes a circuit at armature 321 from the grounded release trunk conductor 237 through armature 327 and its working contact for release relay 302. Release relay 302 thereupon energizes; connects the release trunk conductor 237 to the local holding conductor 316 at armature 323, at the same time removing ground locally from conductor 316; opens a point in the circuit of release magnet 308 and locks itself to conductor 316 at armature 324 through the resting contact and armature 332 and the resting

contact and armature 341; shunts the off normal contacts 309 at armature 314; and at armature 325 prepares the impulsing circuit.

When the calling subscriber manipulates his calling device in accordance with the fourth digit in the desired number, a corresponding number of interruptions are produced in the circuit of line relay 301 of the connector, Fig. 4, in the same manner as described hereinbefore in connection with the intermediate selector, Fig. 3. Upon each deenergization, line relay 301 opens the initial circuit of release relay 302 at armature 321, leaving release relay 302 energized through its previously described locking circuit, and at armature 323 places ground on the operating conductor 315, thereby closing a circuit for vertical magnet 312. By the operation of vertical magnet 312, the wipers 343-345, inclusive, are raised step by step and come to rest opposite the desired level of bank contacts. Relay 305 is energized in multiple with vertical magnet 312 and, being slow acting, maintains its armatures attracted throughout the vertical movement. Upon energizing, relay 305 closes at armature 335 a locking circuit through armature 328 and its working contact for the lower winding of relay 303, thereby maintaining relay 303 energized after its initial circuit is opened at off normal contacts 310, which occurs upon the first vertical step of the switch. Also off normal contacts 309 open at the same time and leave line relay 301 bridged across the line only through armature 314 and its working contact.

At the end of the vertical movement, slow acting relay 305 deenergizes and opens the locking circuit of relay 303 at armature 335, whereupon relay 303 deenergizes and transfers the operating conductor 315 from the vertical magnet 312 to the rotary magnet 311.

When the calling subscriber dials the fifth digit, rotary magnet 311 is operated over the operating conductor 315 and rotates the wipers 343-345, inclusive, into engagement with the set of bank contacts 346-348, inclusive, of the line of substation B. The slow acting relay 305 is, at this time, energized over the operating conductor 315 as before. Relay 305 disconnects the test wiper 344 from the upper winding of switching relay 306 and connects it to busy relay 304 instead, and, at armature 336, places a shunt around armature 332 so as to prevent the talking circuit of relay 303 from being opened in case busy relay 304 energizes during the rotary movement, due to test wiper 344 passing over grounded bank contacts.

The further operation depends upon whether the called line is busy or idle. If it is busy, busy relay 304 is energized through test wiper 344 when the wipers of the connector come to rest on the contacts

of the called line and prepares a locking circuit for itself at armature 331. Accordingly, when the slow acting relay 305 deenergizes, busy relay 304 remains locked up to the release trunk conductor 237 and the locking circuit of release relay 302 is opened at armature 336 on account of the fact that armature 332 is operated. Accordingly, release relay 302 deenergizes and disconnects line relay 301 from in bridge of the conductors 236 and 238 with results to be pointed out hereinafter, at the same time connecting the busy lead 175 which has been connected to the talking circuit at armature 333 of relay 304 to conductor 238 at the normally closed contacts controlled by armature 314. Accordingly, the busy tone is transmitted back to the calling subscriber in a manner to be explained hereinafter.

When the calling subscriber hears the busy tone, he replaces his receiver, whereupon the connection is released in a manner to be described hereinafter.

It will now be assumed that the line of substation B is idle when called. In that case busy relay 304 is not energized when the wipers of the connector land on the called line, and as soon as relay 305 deenergizes a circuit is closed at armature 334 for switching relay 306 as follows: from ground by way of the grounded release trunk conductor 237, armature 331 and its resting contact, upper winding of switching relay 306, resting contact and armature 334, test wiper 344, test contact 347, switching relay 349 of the line switch LS', and stepping magnet 350 to battery. Switching relay 349 of the line switch LS' energizes over this circuit but stepping magnet 350 does not energize on account of the high resistance of switching relay 349. Switching relay 349, on the other hand, is able to energize only part way on account of the usual mechanical inter-locking device between its armature proper and that of the associated line relay. Accordingly, the armature springs of switching relay 349 are moved out of engagement with the associated resting contacts, but the wipers of the switch are not connected up.

In the connector, switching relay 306 energizes over the previously traced circuit through its upper winding; closes a locking circuit for its lower winding at armature 339; places ground on test wiper 344 over a path which is independent of the upper winding of relay 306 at armature 340; and at armatures 337 and 342 connects up the line wipers. Ringing current from the ringing lead 318 is now projected out over the called line intermittently to ring the bridged bell at the called substation and returns to ground over the lower line wiper and through armature 330 of ring cut off relay 303 and its resting contact. As a further

result of the energization of switching relay 306, it disconnects conductor 236 from line relay 301 and connects it instead to the small condenser 313 so as to permit a small amount of the ringing current to pass back to inform the calling subscriber that the called subscriber's bell is being rung. Switching relay 306 also opens the locking circuit of release relay 302 and prepares a locking circuit for ring cut off relay 303 at armature 341. Release relay 302 now deenergizes and disconnects the lower terminal of line relay 301 from conductor 238, at the same time closing a point in the talking circuit. In the incoming selector repeater, as a result of the line relay 301 being disconnected, relays 105 and 106 deenergize. Relay 105, upon deenergizing, opens the locking circuit of the lower winding of the change-over relay 109 at armature 129, whereupon change-over relay 109 deenergizes and places the talking condensers in their proper position in the talking circuit at armatures 137 and 142; opens a further point in its own locking circuit and prepares a holding circuit for release relay 103 at armature 139; removes the shunt from around resistance 117 at armature 138 so as to reduce battery consumption and so as to keep the low wound relay 102 from heating up; and at armature 140 disconnects the junction of the two windings of line relay 107 from the lower talking conductor, at the same time connecting the lower terminal of the lower winding of relay 107 to the lower talking conductor through the high resistance 115. The two windings of relay 107 and resistance 115 in series are now bridged across the upper and lower talking conductors.

In the first selector repeater, Fig. 1, relays 39 and 40 now fall back responsive to the inclusion of the high resistance 115, Fig. 2, in their circuit. Relay 40, upon deenergizing, closes at armature 78 a circuit for relay 35 as follows: from ground by way of armature 64 and its resting contact, armature 78 and its resting contact, armature 81 and its working contact, normally closed contacts controlled by armature 66, and relay 35 to battery. Relay 35 thereupon energizes; closes a locking circuit for itself and opens its initial circuit at armature 66; prepares a circuit at armature 67 for relay 36; and at armature 65 disconnects ground from armature 74 of relay 38 and shunts the lower winding of relay 31. The circuits remain in this condition until the called subscriber responds.

When the subscriber at substation B responds to the ringing of his bell by removing his receiver, ring cut off relay 303 of the connector energizes in the usual manner and closes a locking circuit for itself at armature 328, and at armatures 326 and 330 disconnects the line wipers from its own upper

winding and ground and connects them to the talking conductors 236 and 238.

In the incoming selector repeater, Fig. 2, relays 105 and 106 now feed battery to the called substation B and, consequently, relay 105 energizes over the called line, but relay 106 being differentially wound does not energize at this time. Upon energizing relay 105 shunts high resistance 115 at armature 130 through armature 133 and its resting contact.

In the first selector repeater, Fig. 1, relays 39 and 40 now energize responsive to the high resistance 115, Fig. 2, being short circuited, and relay 40, upon energizing closes at armature 78 a circuit through armature 67 and its working contact for the meter operating relay 36. Relay 36 thereupon energizes; opens the circuit of the slow acting relay 37 and closes a locking circuit for itself at armature 70; and at armature 68 applies booster battery to release trunk conductor 18 through the working contact and armature 71 and resistance 73, at the same time removing direct ground from release trunk conductor 18 at the normally closed contacts controlled by armature 68.

Responsive to the application of booster battery to release trunk conductor 18, which conductor is now connected to private normal conductor 4 of the calling line through test wiper 14 of the line switch LS and armature 9 and its working contact, the marginally adjusted meter 16 is operated to register the call. This meter may be used, as shown, as a totalizer of outgoing calls on a party line, or it may be used on an individual line as an indicator of the amount of charge to be assessed the subscriber on that line. In any event, the meter magnet 16 energizes and advances the associated number wheels in the usual manner to register the completed connection.

In the first selector repeater, the slow acting relay 37 deenergizes after an interval, responsive to its circuit being opened at armature 70 of relay 36, and removes the booster battery from the release trunk conductor 18 at armature 71, at the same time reapplying direct ground to the said conductor 18. The meter magnet 16 may be adjusted to maintain its armature attracted after the booster battery is removed and until the calling line becomes idle, or if desired it may retract its armature when the booster battery is removed.

The calling and called subscribers may now converse with each other as desired, and when they have finished conversing they replace their respective receivers.

Assuming that the subscriber at substation B replaces his receiver first, relay 105 of the incoming selector repeater, Fig. 2, deenergizes when the called subscriber replaces his receiver and reinserts the high resistance 130

115 into the circuit, whereupon relays 39 and 40 of the first selector repeater, Fig. 1, respond by retracting their armatures. The circuits remain in this condition until the calling subscriber replaces his receiver.

When the subscriber at substation A replaces his receiver line relay 32 of the first selector repeater deenergizes and opens the circuit of line relay 107 of the incoming selector repeater, Fig. 2, whereupon line relay 107 deenergizes and opens the circuit of the repeating relay 102 at armature 134 with results to be pointed out hereinafter. As a further result of the deenergization of line relay 32 of the first selector repeater, it opens the circuit of the associated release relay 33 at armature 59, at the same time incidentally applying ground to the operating conductor through armature 62 and its working contact. The slow acting relay 34 now energizes through armature 84 and its working contact, but this does not have any particular utility at this time.

After the interval for which it is adjusted, the slow acting release relay 33 deenergizes, removes ground from the release trunk conductor 18 at armature 61, and also opens the locking circuits of relays 35 and 36, permitting these relays to deenergize. Responsive to the removal of the ground potential from release trunk conductor 18 the switching relay 5 of the line switch LS deenergizes. As a further result of the deenergization of release relay 33, it removes ground from conductor 51 at armature 60, whereupon switching relay 41 deenergizes disconnecting the wipers 86 and 88. As a still further result of the deenergization of release relay 33, it opens the circuit of the slow acting relay 34 and closes the release magnet circuit at armature 62. Release magnet 42 now energizes through off normal contacts 43 and restores the wipers of the switch to their normal position in the usual manner. The circuit of release magnet 42 is opened at off normal contacts 43 when the switch wipers reach their normal position.

In the incoming selector repeater, Fig. 2, as a result of the above mentioned opening of the circuit of repeating relay 102 by line relay 107, relay 102 deenergizes and opens the circuit of release relay 103 at armature 124. Incidentally, the slow acting relay 104 energizes, but this does not have any particular utility at this time.

At the end of the interval for which it is adjusted, the slow acting release relay 103 deenergizes and removes ground from conductor 171 at armature 126, thereby removing ground from release trunk conductor 162 and opening the circuit of switching relay 110. Accordingly, switching relay 110 deenergizes and disconnects the wipers 148 and 150. As a further result of the deenergization of release relay 103, it opens the cir-

cuit of relay 104 and closes the release magnet circuit at armature 127, whereupon release magnet 111 energizes through off normal contacts 112 and restores the switch to normal in the usual manner.

Responsive to the removal of ground from release trunk conductor 162 of the intermediate selector, Fig. 3, switching relay 205 of the intermediate selector, relays 303 and 306 of the connector and switching relay 349 of the line switch LS' deenergize. Responsive to the deenergization of switching relay 205 of the intermediate selector release magnet 206 energizes through off normal contacts 208, resting contact and armature 225, resting contact and armature 222, and armature 231 and its resting contact and restores the wipers of the switch to normal in the usual manner.

Release magnet 206 also opens the contacts 207 so as to prevent an operation of rotary magnet 210 in case stepping relay 204 should energize during the releasing operation due to test wiper 234 rotating back over grounded test contacts.

In the connector, Fig. 4, responsive to the deenergization of relay 306, release magnet 307 energizes through off normal contacts 308, resting contact and armature 324, resting contact and armature 332, resting contact and armature 341, and the normally closed contacts controlled by armature 323 to battery and restores the switch to normal in the usual manner. The entire connection is now released.

It will now be assumed that the subscriber at substation A, Fig. 1, desires to converse with the subscriber at substation A' on the same line. In order to do this it will be necessary for the subscriber at substation A to call a special number which will result in a connection being extended to a so called reverting call switch and thence to a special ring-back set which will ring the bells of the two subscribers alternately. Accordingly, the subscriber at substation A removes his receiver and it will be assumed that the line switch LS selects the first selector repeater shown in the drawing, and that when the subscriber manipulates his calling device in accordance with the first digit in the desired number the first selector repeater selects the trunk comprising conductors 89-91, inclusive, extending to the intermediate selector, Fig. 5. This intermediate selector is denoted by a dotted rectangle, but may be identical with the intermediate selector shown at Fig. 3.

When the calling subscriber manipulates his calling device in accordance with the second digit in the desired number, the intermediate selector raises its wipers 401-403, inclusive, opposite the desired level of bank contacts and selects an idle trunk, which trunk it will be assumed is the one comprising conductors 404-406, inclusive. When

this occurs, line relay 412 of the reverting call switch energizes over conductors 404 and 406 and closes at armature 436 a circuit for release relay 415. Release relay 5 415 thereupon energizes and places ground on conductor 407 at armature 403, and at armature 442 opens a point in the circuit of release magnet 423 and prepares a circuit for stepping magnet 424, thereby preparing the 10 switch for operation.

When the calling subscriber manipulates his calling device in accordance with the third and last digit in the desired number, the circuit of line relay 412 is opened a corresponding number of times in the hereinbefore described manner at the first selector repeater. Each time line relay 412 deenergizes responsive to one of these interruptions, it closes at armature 436 a circuit through 15 armature 442 and its working contact, normally closed contacts controlled by armature 445, and series relay 417 for stepping magnet 424. By the operation of stepping magnet 424 wipers 421 and 422 are advanced step by 20 step and come to rest on the bank contacts in which conductors 469 and 470 terminate. Relay 417 is energized in series with stepping magnet 424 and, being slow acting, maintains its armature attracted throughout the stepping 25 movement. Upon energizing, relay 417 closes a locking circuit for itself at armature 447, and opens a point in the circuit of relay 411 at armature 446. Upon the first step of the switch off normal contacts 425 close, 30 whereupon relay 416 energizes and prepares a circuit for release magnet 423 at armature 444, at the same time preparing a circuit for relay 411.

At the end of the stepping movement relay 417 deenergizes and closes a point in the circuit of relay 411 at armature 446.

The calling subscriber, having dialled the special number according to previous instructions, now replaces his receiver, whereupon 45 line relay 38 deenergizes and opens the outgoing control circuit at armature 58 and the circuit of release relay 33 at armature 59.

In the reverting call switch, Fig. 5, responsive to the opening of the outgoing control circuit by the first selector repeater, line relay 412 deenergizes and completes at armature 436 a circuit through armature 442 and its working contact, working contact and armature 445, resting contact and armature 446 armature 448 and its resting contact for relay 411. Relay 411 thereupon energizes and disconnects conductors 494 and 406 from line relay 412 and extends them by way of relay 419 and resistance 426 to armatures 451 and 453, respectively. Relay 411 also closes a circuit for relay 415 at armature 432 before the latter has had time to deenergize, and at armature 434 connects the low wound relay 414 through the nor-

mally closed contacts controlled by relay 440 to the release trunk conductor 405. The release trunk conductor 405 is connected back through the release trunk conductor 90 of the intermediate selector, test wiper 70 of the first selector repeater, armature 80 and its working contact, armature 60 and its working contact to ground through the lower winding of the marginal switch through relay 31. Relay 31 now energizes on account of the excess current drawn by the low wound relay 414, Fig. 5; locks itself to the grounded release trunk conductor 31 at armature 551, at the same time connecting release trunk conductor 55 and conductor 51 together so as to form a holding circuit straight through the switch; disconnects ground from armature 59 of line relay 32 at armature 56 so as to prevent the switch from releasing prematurely; and at armatures 54 and 57 disconnects the wipers 86 and 88 from the back bridge relays 40 and 39 and connects them instead to the incoming trunk conductors 17 and 19, at the same time disconnecting said conductors from the line relay and talking condensers. The connection is now switched straight through the first selector repeater without any talking condensers or battery feed bridges and a clear path is provided whereby the ringing current may be projected back to the calling line from the ringing equipment.

In the reverting call switch, Fig. 5, responsive to being connected up to the release trunk conductor 405, as hereinbefore described, the low wound relay 414 energizes in series with the marginal relay 31 of the first selector repeater and connects the release trunk conductor 405 to ground through the upper winding of relay 413. This does not have any particular effect at 105 this time, however, because of the fact that the release trunk conductor is, for the time being, grounded in the first selector repeater.

After the interval for which it is adjusted, release relay 33 of the first selector repeater, Fig. 1, deenergizes and removes ground from release trunk conductor 18 at armature 31 and from conductor 51 at armature 60. When this occurs, the connection is held up solely through the ground applied to release trunk conductor 405 of the reverting call switch through armature 441 and its working contact and the upper winding of relay 413. Accordingly, relay 413 energizes in series with the switching relays of the line switch LS and of the first selector repeater, Fig. 1, and in series with relay 414 of the reverting call switch, all of which are connected to the release trunk conductor of the established connection. Upon energizing, relay 413 locks itself to the grounded local conductor 497 at armature 439; sep-

arates the two windings of line relay 412, and connects the upper winding to battery and the lower winding to ground at armatures 438 and 437, respectively; and at armature 440 places ground directly on release trunk conductor 405 independent of its own upper winding, at the same time disconnecting relay 414 which promptly deenergizes and closes a circuit through the working contact and armature 423 and the normally closed contacts controlled by armature 452 for the wiper connecting relay 451. Relay 451 thereupon energizes and closes a local locking circuit for itself at armature 452, at the same time opening its initial circuit. Relay 420 also connects up the line wipers 422 and 421 at armatures 451 and 453, respectively. The wipers 421 and 422 are now connected to the common ringing leads 469 and 470, over which ringing current is projected alternately. This ringing current flows back over the established connection to the calling line and operates the bells at substations A and A' alternately.

When the subscriber at substation A' responds to the ringing of his bell by removing his receiver, the ring cut off relay 419 in the reverting call switch, Fig. 5, operates in the well known manner and closes at armature 450 a circuit for relay 418 which thereupon energizes and locks itself to ground through off normal contacts 425 at armature 449 and opens the circuit of relay 411 at armature 448. Relay 411 now deenergizes and opens the circuit of release relay 415 at armature 432 and shifts the conductors 404 and 406 back to the line relay again, thereby removing the ringing current from the calling line. Line relay 412, which is now supplied with battery and ground locally, now feeds talking battery to the calling line and is, accordingly, energized and closes a circuit for release relay 415 at armature 436 before it has had time to deenergize.

When the subscriber at substation A notes that his bell is no longer ringing he knows that the subscriber at substation A' has responded and he takes off his receiver, whereupon the conversation may proceed.

When the conversation is terminated the two subscribers replace their receivers and when they have both done so the circuit of line relay 412 of the reverting call switch is opened. Accordingly, line relay 412 deenergizes and opens the circuit of release relay 415 at armature 436. Release relay 415, upon deenergizing, closes at armature 442 a circuit through the working contact and armature 444 of the off normal relay 416 for release magnet 423. Release magnet 423 now energizes and restores the wipers 421 and 422 to normal position in the usual manner. When the normal position is reached off normal contacts 425 separate, de-

energizing relay 416 and opening the circuit 65 of release magnet 423 at armature 444.

As a further result of the deenergization of relay 415, it removes ground from the local locking conductor 407 at armature 443, whereupon relays 413 and 420 deenergize. Relay 413, upon deenergizing, removes ground from release trunk conductor 405 at armature 440, whereupon the intermediate selector is released in the hereinbefore described manner. As a further result of the removal of ground potential from the release trunk conductor, switch through relay 31 of the first selector repeater deenergizes and closes the release magnet circuit at armature 56, whereupon the first selector repeater is restored to normal in the hereinbefore described manner.

It will be understood that in case the subscriber at substation A desires to call another subscriber in his local office, he operates a first selector repeater to some level other than the three levels shown, whereupon the first selector repeater seizes an intermediate selector, whose position in the train is that of a thousands selector. This intermediate selector may be identical with the intermediate selector shown in Fig. 3, and when it is operated in accordance with the second digit in the desired number it seizes a similar intermediate selector whose position in the switch train is that of a hundreds selector. Accordingly, when the third digit is dialled this latter intermediate selector is operated to seize a connector, like the one shown in Fig. 4, which then responds to the last two digits to complete the connection to the desired line.

In order to explain how a connection is completed between a so called inverted office and an ordinary two-wire office, it will be assumed that the subscriber at substation A desires to converse with the subscriber at substation B', Fig. 7, whose line terminates in a two-wire office of the ordinary type, that is, one in which the connector in use 110 is arranged to feed battery both ways. It will be assumed further that when the subscriber at substation A removes his receiver the line switch LS selects the first selector repeater shown in the drawings, and that when the first digit in the desired number is dialled the first selector repeater, after raising its wipers to the desired level, selects the trunk line TL' comprising conductors 95 and 96, which extends to the incoming selector repeater, Fig. 6, in the distant office. Accordingly, line relay 501, Fig. 6, which is bridged across the conductors of the trunk line TL' through off normal contacts 512 and the normally closed contacts 535, energizes over the trunk line and closes at armature 52 a circuit through the resistance 517 for the

repeating relay 503. Relay 503 now energizes and closes at armature 526 a circuit for release relay 504. Release relay 504 energizes and prepares the switch for operation 5 at armature 529, and at armature 528 places ground upon the local locking conductor 516, thereby closing a circuit through armature 538 and its resting contact for relay 502. Relay 502 energizes and closes a locking circuit for itself at armature 523, and 10 at armature 524 closes the bridge across the trunk conductors through the upper winding alone of relay 501, at the same time disconnecting one terminal of the lower winding so as to improve the impulsive circuit. The placing of ground upon the local locking conductor 576 results also in a circuit being closed for the lower winding of relay 507. Relay 507, however, does not energize 15 at this time on account of the fact that the lower winding is composed of a small number of turns of wire having a relatively high resistance.

When the calling subscriber manipulates his calling device in accordance with the second digit of the desired number, line relay 501 is deenergized a corresponding number of times owing to the fact that its circuit is interrupted at the first selector repeater in the hereinbefore described manner. Each time relay 501 deenergizes relay 503 deenergizes on account of the fact that relay 501 opens its circuit at armature 521. Each time it deenergizes, relay 503 closes at 35 armature 526 a circuit through armature 529 and its working contact, and armature 540 and its resting contact for vertical magnet 515. By the operation of vertical magnet 515 the wipers of the switch are raised step by step and come to rest opposite the desired level of bank contacts. The slow acting relay 505 energizes in multiple with vertical magnet 515 upon the first impulse of current being delivered to the latter and remains energized throughout the vertical movement. At armature 531 relay 505 short circuits the resistance 517 so as to enable relay 503 to respond better. Also, relay 505 closes at armature 532 a point in the circuit of stepping relay 506, which, upon the closure of the off normal contacts 513, is completed from the grounded conductor 516 through the working contact and armature 532, resting contact and armature 537 and off normal contacts 513. Upon energizing, relay 506 closes a locking circuit for itself at armature 533 which includes the interrupter contacts of the rotary magnet 514, and at armature 533 prepares a circuit for the rotary magnet.

At the end of the vertical movement slow acting relay 505 deenergizes and completes the rotary magnet circuit at the normally closed contacts controlled by armature 532. Rotary magnet 514, accordingly, energizes 65 and advances the wipers into engagement

with the first set of bank contacts in the selected level. From this point on, the selecting operation is the same as has been described hereinbefore, and the wipers continue to advance until an idle trunk is reached which trunk, it will be assumed, is the one comprising conductors 545-547, inclusive. When this idle trunk is reached switching relay 508 energizes; opens the initial circuit of relay 502 at armature 528, 70 leaving relay 502 energized through armatures 534 and 523; disconnects vertical magnet 515 at armature 540; disconnects armature 532 of relay 505 at armature 537 so as to prevent relay 505 from again energizing the stepping relay 506; opens the test circuit and places ground on the test wiper 543 at armature 539; and at armatures 536 and 541 connects up the line wipers 542 and 544. When this occurs, line relay 601 of the selector S, to which the seized trunk extends, energizes over conductors 545 and 547 and through the back bridge of the incoming selector repeater. Relay 601 closes at armature 611 a circuit for release relay 602 which 80 energizes and prepares the selector for operation in the well known manner at armatures 612 and 613.

The above mentioned back bridge of the incoming selector repeater, Fig. 6, includes 95 armature 530 and its resting contact, the upper winding of the electropolarized relay 507, working contact and armature 525, left hand winding of the impedance 509, and armature 527 and its working contact. Current is now flowing through both windings of the electropolarized relay 507, but in opposite directions. Accordingly, the relay is not operated.

When the calling subscriber dials the third 105 digit of the desired number, line relay 501 of the incoming selector repeater repeats the interruptions produced in its circuit to relay 503, which deenergizes a corresponding number of times and opens the circuit of line 110 relay 601 of the selector S at armature 527 upon each deenergization. Responsive to the deenergizations of relay 601 the selector S raises its wipers opposite the desired level of bank contacts and rotates them into engagement with an idle trunk which, it will be assumed, is the one comprising conductors 621-623, inclusive. When this occurs, switching relay 603 energizes in the usual manner and switches the connection through 115 to the connector C. When this occurs, line relay 632 of the connector C energizes with the result that the switch is prepared for operation in the usual manner.

In the incoming selector, Fig. 6, as a further result of the above mentioned response of the line relay 503 to the third digit, relay 505 energizes and is maintained energized throughout the calling of this digit. At armature 530 relay 505 completes the bridge 120

across the wipers 542 and 544 by a more direct path which includes the windings of relay 507 and impedance 509. This is the usual expedient made use of in order to 5 improve the impulsing circuit.

When the subscriber dials the next two digits the connector C is operated in the usual manner to extend the connection to the line of substation B. When the connection 10 is completed, ringing current is sent out from the connector C in the usual manner to ring the called subscriber's bell, and when the called subscriber responds the back bridge relay 631 is connected up and the 15 ringing current source is disconnected, whereupon back bridge relay 631 energizes over the called line and reverses the current flow in conductors 621 and 623, whereupon the electropolarized relay 507 of the incoming 20 selector repeater, Fig. 6, responds by attracting its armatures 534 and 535. Armature 534 opens the circuit of the slow acting relay 502, and by the operation of armature 535 the high resistance 516 is inserted 25 into the bridge across the conductors of the trunk line TL'. This bridge now includes the upper winding of relay 501, working contact and armature 524, resistance 516, and armature 535 and its working contact. 30 In the first selector repeater, Fig. 1, the hereinbefore described switch over operation takes place responsive to the increase of the resistance of the front bridge at the incoming selector repeater. Specifically, relays 39 and 40 deenergize, and the latter 35 closes a circuit for relay 35 which energizes with the hereinbefore described results.

In the incoming selector repeater, the slow acting relay 502 deenergizes after an interval, responsive to the opening of its locking circuit by the electropolarized relay, and shifts the bridge across the trunk line TL' so as to substitute the lower winding of relay 501 for the high resistance 516. When 45 this occurs, relays 39 and 40 in the first selector repeater, Fig. 1, energize again and relay 40 closes a circuit for meter operating relay 36 through armature 67 and its working contact of relay 35, with the result that 50 the meter on the line of substation is operated in the hereinbefore described manner.

The talking circuit is now complete and the two subscribers may converse as desired, and when the conversation is terminated they replace the receivers. Assuming that the subscriber at the substation B' replaces his receiver first, back bridge relay 631 deenergizes and restores the current flow in the associated trunk conductors to normal, 55 whereupon the electropolarized relay at the incoming selector, Fig. 6, responds by retracting its armatures. At armature 535 relay 507 reinserts the high resistance 516 into the circuit, whereupon relays 39 and 40, 60 at the first selector repeater, Fig. 1, deener-

gize and the latter operates the common supervisory equipment in a manner to be pointed out hereinafter.

When the subscriber at substation A replaces his receiver, the first selector repeater 70 and the line switch LS are released in the hereinbefore described manner.

Prior to the release of the first selector repeater, the circuit of the line relay of the incoming selector repeater is opened at 75 armature 58 of line relay 32 of the first selector repeater. Responsive to this, line relay 501 deenergizes and opens the circuit of the repeating relay 503 at armature 521. Repeating relay 503 thereupon deenergizes 80 and opens the circuit of the line relay of the connector C at armature 527, and at armature 526 opens the circuit of release relay 504. Incidentally the circuit of relay 585 is closed through armature 529 and its working contact, but this does not have any particular utility at this time.

At the end of the interval for which it is adjusted, release relay 504 deenergizes and removes ground from the local conductor 90 516 at armature 528, thereby removing ground at one point from release trunk conductor 546 of the selector S. However, if the release relay, not shown, of the connector C, has not yet fallen back, the selector 95 S and the connector C remain grounded for the time being. As a further result of the deenergization of relay 504, it opens the circuit of relay 505 and closes a circuit through off normal contacts 511 for release magnet 100 510, whereupon the incoming selector repeater is restored to normal position in the usual manner.

In the connector C, responsive to the opening of the circuit of its line relay, the said 105 switch is released in the usual manner and ground is removed from the release trunk conductor by the release relay, not shown, whereupon the switching relay 603 of the selector S deenergizes and the said selector 110 S is restored to normal position in the usual manner. The entire connection is now released.

It will now be explained more fully just what occurs when a busy line, the line of 115 substation B, Fig. 4, for example, is called. The incoming selector repeater, Fig. 2, is arranged so that there is no talking connection between the trunk conductors and the wipers thereof, until the switch over operation has taken place after the connector has been operated. It has been explained hereinbefore how the switch over operation takes place responsive to the connector, Fig. 4, connecting with the line of substation B when 120 it is idle. This switch over operation, it will be remembered, takes place responsive to line relay 301 of the connector being disconnected. It has been pointed out hereinbefore that line relay 301 is likewise discon- 125 130

nected when the called line is busy owing to the fact that busy relay 104 opens the circuit of release relay 302 which deenergizes and disconnects relay 301 from in bridge of 5 conductors 236 and 238 at armature 314. Responsive to this the usual switch over operation takes place, completing the talking circuit at the incoming selector repeater as hereinbefore pointed out. Accordingly, the 10 busy tone placed on the lower heavy talking conductor at armature 133 of busy relay 304 is transmitted back to the calling line. It will be noted that battery is intermittently superimposed on the busy tone current flowing in lead 175. This is done so as to give a calling operator flashing supervision, as pointed out in my co-pending application hereinbefore referred to. In the case where the connection is extended from the 15 line of substation A, Fig. 1, through the switches shown in Figs. 1-4, inclusive, responsive to the application of battery to the lower talking conductor, relays 105 and 106 of the incoming selector repeater, Fig. 2, 20 energize because their lower windings are connected in series between ground and the lower talking conductor. Accordingly, a circuit is closed at armature 129 and its working contact of relay 105 and through 25 the normally closed contacts controlled by armature 139 and armature 132 and its working contact for maintaining release relay 103 operated independent of the repeating relay 102 which is held up by line relay 107. This 30 operation, however, is merely incidental at this time, and its function will be pointed out hereinafter. Relay 106, upon energizing, connects battery through the resistance 116 at armature 131 to the lower trunk conductor 35 of the switch through the normally closed contacts controlled by armature 137. This 40 is for the purpose of operating the supervisory lamp at a calling operator's position when the connection to the incoming selector repeater is set up by an operator, and is fully 45 explained in my copending application hereinbefore referred to. In the present case, however, this battery potential, upon being applied to the lower trunk conductor, brings 50 about the operation of relay 39 of the first selector repeater, Fig. 1, which is connected between the lower talking conductor and ground through the resting contact and armature 57. Relay 39, upon energizing, closes 55 at armature 76 a circuit for maintaining relay 33 energized independent of the line relay.

As soon as battery is removed from conductor 175 by the busy machine, Fig. 4, the 60 circuits in the incoming selector repeater, Fig. 2, and the first selector repeater, Fig. 1, are restored to their previous condition. It may be pointed out that the interrupter which controls the application of battery to 65 the busy lead 175 operates slowly and the

time between the successive applications of battery is sufficiently long to permit the connection to be released.

From the above it will be understood that if a call is extended to an operator's 70 position through either the first selector repeater, Fig. 1, or the incoming selector repeater of Fig. 2, the operator may hold the connection established by applying battery to the lower talking conductor, with the result pointed out hereinbefore. 75

Referring now to Fig. 3, it will be noted that in case the intermediate selector is not able to find an idle trunk and rotates off the last trunk, the eleventh rotary step contacts 213 close and connect the busy conductor 175 to the lower wiper 235. Then, as soon as the switch over operation has taken place, which it does as soon as switching relay 205 operates and switches the connection on to the open wipers, the busy current is transmitted back to the calling subscriber as explained hereinbefore. The same thing occurs if the incoming selector repeater, Fig. 2, is unable to find an idle 80 trunk. 85

Referring now to Fig. 1, in case the first selector repeater is unable to find an idle trunk, the eleventh rotary step springs 46 and 47 are operated and the switching relay 41 is prevented from energizing upon its circuit being opened at contacts 46. This is so as to prevent any possibility of a false operation of a calling subscriber's meter, which might possibly occur in case 90 relay 41 were permitted to energize at this time. Spring 47 connects a busy signalling conductor 23 to the lower trunk conductor through off normal spring 44 and its upper contact so as to inform the calling subscriber of the busy condition. 100 105

It will be understood that the intermediate selector, shown in Fig. 5, is equipped with the same busy signalling arrangements as the intermediate selector shown in Fig. 3. 110

Referring now to Fig. 7, it will be noted that the connector C is provided with a busy relay 640 which is energized in the usual manner to place a busy tone on the lower heavy talking conductor whenever the called 115 line is busy. Since the busy relay 640 is not provided with contacts for reversing the current flow in the trunk conductors of the connector, no switch-over operation takes place as is the case when the connector shown in 120 Fig. 4 lands on a busy line. However, the arrangements in the incoming selector repeater of Fig. 6 and the first selector repeater of Fig. 1 are such that it is not necessary for the switchover operation to be performed for busy signalling current to be transmitted back to a calling subscriber, the talking condensers being connected up at all times. 125

Referring now to the selector S, when this 130

selector is unable to find an idle trunk the eleventh rotary step contacts 604 and 605 operate. Contacts 604 are for the purpose of preventing the switching relay 603 from operating, and the contacts 605 connect the busy signalling conductor to the trunk conductor 547 to send back the busy tone to the calling subscriber.

In case the incoming selector repeater of Fig. 6 is unable to find an idle trunk, the eleventh rotary step contacts associated therewith are closed, whereupon the busy tone is transmitted back over the lower heavy talking conductor to the line of the calling subscriber.

Arrangements have been provided in the first selector repeater, Fig. 1, for suitably supervising the connections. The lamp 26 is individual to the first selector repeater and is lighted when the first selector repeater is seized. The circuit of the lamp 26 is as follows: from ground by way of armature 64 of relay 34 and its working contact, conductor 97 and the pilot relay to battery. Relay 28 energizes in series with the lamp 26 and lights the associated pilot lamp at the same time preparing a circuit which may be completed through the push button 30 to any desired slow alarm device in case it is desired to have an alarm operate at certain times of the day when a call is originated. As soon as the first digit is dialled and an idle trunk is selected, switching relay 41 energizes and opens the circuit of the slow acting relay 34 at armature 84 and connects relay 34 to the impulsing circuit in place of vertical magnet 48. Relay 34 thereupon deenergizes and shifts the circuit of the lamp 26 so as to include armature 64 and its resting contact, armature 78 and its working contact of repeating relay 40, and armature 67 and its resting contact.

During the dialling of each digit, the slow acting relay 34 energizes and opens the circuit of the lamp 26 at armature 64. However, the initial circuit of the lamp 26 over conductor 97 is reclosed. In case it is so desired, the lamp 26 will be extinguished during the dialling of each digit if the conductor 97 is omitted. Furthermore, the omission of conductor 97 has the effect of preventing lamp 26 from becoming lighted until the above traced alternate circuit is closed through armature 78 and its working contact responsive to the de-energization of relay 34, which occurs following the operation of switching relay 41 when an idle trunk is seized. In any event, when the switch-over operation takes place and relay 35 is energized, the circuit of the lamp 26 is opened at armature 67 and, as soon as the meter operating relay 36 responds when the called man answers, a circuit is prepared at armature 69 for the supervisory lamp 27. This circuit is not completed at this time, however, on account of the fact that it must pass through the resting contact and armature

78 of relay 40 which is now energized, but, as soon as the called subscriber replaces his receiver, the circuit of lamp 27 is completed from ground at armature 64 through the resting contact thereof, armature 78 and its resting contact, armature 81 and its working contact, working contact and armature 69, lamp 27, and the associated pilot relay to battery. The lighting of this lamp indicates that the connection is being held up by the called subscriber after the calling subscriber has replaced his receiver. The circuit of this lamp, of course, is opened when the connection is released.

In order to explain how the invention is applicable to a system containing only inverted offices, Fig. 8 should be substituted for Fig. 1. The first selector repeater shown in Fig. 8 differs from that shown in Fig. 1 principally in that the trunk conductors of the latter are not connected through condensers to the wipers until after the switch-over operation occurs, whereas, in the former, they are connected through to the wipers as soon as the switch operates so that busy signalling currents, and the like, may be transmitted through the switch without the switch-over operation taking place when a call is extended to a two-wire office of the ordinary type. When all offices in the system are of the inverted type, the first selector repeater shown in Fig. 8 may be used and better impulsing may be obtained because the impulsing circuit is not handicapped by the connection of the talking condensers while the switch is in dialling position. Another difference which may be pointed out between the first selector repeater of Fig. 8 and that of Fig. 1 is that the release trunk conductor of the latter switch is grounded through the low resistance winding of the switch-through relay 721 while the switch is in dialing position, whereas arrangements have been made for grounding the release trunk conductor of the first selector repeater of Fig. 1 independent of the low resistance winding of its switch-through relay at all times. This precaution is considered necessary in Fig. 1 on account of the fact that the magnets of the rotary line switches having access to this selector repeater are of a relatively low resistance type and draw a fairly heavy current during rotation, but, on the other hand, the magnets of the rotary line switches, such as the rotary line switch LS², Fig. 8, having access to the first selector repeater of Fig. 8, are of a later type having improved magnets of a somewhat higher resistance which do not draw the heavy current required for the former type of rotary line switches.

In order to enable the operation to be understood best, it will be assumed that the subscriber at substation A², Fig. 8, desiring to converse with the subscriber at substa-

tion B, Fig. 4, removes his receiver. It will be assumed further that the line switch LS^2 , which, aside from the somewhat higher resistance of its motor magnet, is similar to the line switch LS , selects the associated first selector repeater shown in the drawing.

When the first selector repeater is seized, line relay 722 energizes over the calling line and closes at armature 745 a circuit through the normally closed contacts controlled by armature 766 for the upper winding of relay 729 in series with relay 728. Relays 728 and 729 thereupon energize. Relay 729, upon energizing, closes one point in a locking circuit for itself at armature 763; connects relay 724 to the operating lead at armature 764 in multiple with vertical magnet 736; disconnects the right hand terminal of the lower talking condenser at armature 765 and short circuits relay 727 through armature 743 and its resting contact so as to keep relay 727 out of the impulsing circuit during the dialling period; disconnects relay 725 at armature 762; connects release trunk conductor 782 to the local locking conductor 784 at armature 761; removes the short circuit from the lower winding of relay 721 at armature 760, at the same time closing a circuit for the associated supervisory lamp 737; and at armature 759 disconnects the right hand terminal of the upper talking condenser from its normal position in the talking circuit and connects it through off normal contacts 733 and its lower contact to the dial tone lead 735. Relay 728, upon energizing in series with relay 729, closes at armature 758 another point in the locking circuit of relay 729.

As a further result of the energization of line relay 722, it closes at armature 746 a circuit for release relay 723 which thereupon energizes; prepares the operating circuit for rotary magnet 733 at armature 748; opens a point in the circuit of release magnet 732 at armature 749 and prepares a circuit for vertical magnet 736; and at armature 747 connects ground from the low resistance lower winding of the marginally adjusted switch-through relay 721 to the local locking conductor 784. Conductor 784 is now connected through armature 761 and its working contact to the release trunk conductor 782. Accordingly, the usual holding circuit for the switching relay of the line switch LS^2 is closed before the associated line relay has had time to deenergize. As a further result of the ground potential being placed upon the local locking conductor 784, a local locking circuit is completed for the lower winding of relay 729 through armature 758 of relay 728 and its working contact and armature 763 and its working contact.

When the calling subscriber dials the first digit, line relay 722 deenergizes a corresponding number of times and closes at arm-

mature 746 a circuit through armature 749 and its working contact and armature 769 and its resting contact for vertical magnet 736. By the operation of vertical magnet 736, the wipers 772-774, inclusive, are raised 76 opposite the desired level of bank contacts. Relay 724 is energized from the operating conductor through the working contact and armature 764 and, being slow acting, maintains its armatures attracted throughout the 75 vertical movement. Upon energizing, relay 724 completes at armature 760 a circuit through armature 768 and its resting contact and the off normal contacts 734 which close as soon as the switch moves off normal 80 for the stepping relay 726. Stepping relay 726 thereupon energizes and closes a locking circuit for itself at armature 754 as follows: from ground by way of the resting contact and armature 743, working contact and armature 765, resting contact and armature 744, armature 771 and its resting contact, working contact and armature 754, interrupter contacts 755 of the rotary magnet 733, off normal contacts 734, and stepping relay 726 90 to battery. Relay 726 also prepares a circuit for rotary magnet 733 at armature 753. As a further result of the energization of relay 724, it closes an auxiliary locking circuit for the lower winding of relay 729 95 at the normally open contacts controlled by armature 750 so as to prevent the change-over relay 729 from deenergizing at this time when its initial locking circuit is opened by relay 728, which deenergizes on account of 100 the fact that its circuit is opened at armature 745 upon each deenergization of line relay 722.

At the end of the vertical movement, relay 728 energizes again and closes the initial 105 locking circuit of relay 729 and an instant later the slow acting relay 724 deenergizes and completes a circuit through armature 753 and its working contact for rotary magnet 733. Rotary magnet 733 thereupon energizes and advances the wipers into engagement with the first set of bank contacts in the selected level at the same time opening its interrupter contacts 755 to deenergize stepping relay 726. The remaining portion 110 of the trunk selecting operation is the same as has been described hereinbefore. Accordingly, the first selector repeater selects an idle trunk, which trunk, it will be assumed, is the one comprising conductors 115 92-94, inclusive. When this idle trunk is reached, switching relay 730 energizes over the following circuit: from ground by way of the local locking conductor 734, switching relay 730, interrupter contacts 755, and thence to battery through the off normal contacts 734 and stepping relay 726. Upon energizing, relay 730 disconnects vertical magnet 736 at armature 769; disconnects armature 750 of relay 724 at armature 768 120 125 130

so as to prevent the said armature 750 from operating the stepping relay 726 again; opens the test circuit and grounds test wiper 733 at armature 767; and at armatures 766 and 771 connects up the wipers 772 and 774 at the same time disconnecting the upper winding of relay 729 from the circuit of relay 728. Relay 728 is now maintained energized over the bridge across conductors 92 and 94 in the incoming selector repeater, Fig. 2, and the return circuit is grounded through the working contact and armature 771 of relay 730, armature 744 and its resting contact, armature 765 and its working contact, and armature 743 and its resting contact.

In the incoming selector repeater, Fig. 2, line relay 107 energizes with the result that the switch is prepared for operation in the hereinbefore described manner.

When the calling subscriber dials the second digit, line relay 722 is deenergized a number of times and opens the circuit of the line relay of the incoming selector repeater, Fig. 2, at armature 745 upon each deenergization, with the result that the incoming selector repeater is operated in the hereinbefore described manner. Line relay 722, upon each deenergization, also closes at armature 746 a circuit through armature 749 and its working contact and the working contact and armature 764 for the slow acting relay 724 which energizes and completes the auxiliary locking circuit of the lower winding of relay 729 at the normally open contacts controlled by armature 750 for the reason pointed out above.

The remaining digits in the desired number are called in the same manner and when the connector completes its operation and causes the switch-over operation in the incoming selector repeater, Fig. 2, to take place, the resistance in the bridge across the trunk conductors of the latter switch is increased by the introduction of the resistance 115, whereupon relay 728, Fig. 8, deenergizes and opens the locking circuit of the switch-over relay 729. Relay 729 thereupon deenergizes; completes the talking circuit at armatures 759 and 765; shunts out the lower winding of relay 721 at armature 760; shifts the connection of the release trunk conductor 782 with the local locking conductor 784 at armature 761 so that it includes the normally closed contacts controlled by armature 761 and the normally closed contacts controlled by armature 751 so as to enable the metering operation to take place; opens a further point in its own locking circuit at armature 763; prepares a circuit for relay 724 at armature 764; and at armature 762 closes a circuit for relay 725 which includes armature 748, normally closed contacts controlled by armature 750,

and armature 753. Relay 725 now energizes in preparation for the metering operation.

When the called subscriber responds, the resistance 115 at the incoming selector repeater, Fig. 2, is short circuited as hereinbefore described, whereupon relays 727 and 728 in the first selector repeater, Fig. 8, energizes. Relay 728, upon energizing, completes at armature 758 a circuit through resistance 735 and the resting contact and armature 764 for relay 724. Relay 724 thereupon energizes; closes a locking circuit for itself at the normally open contacts controlled by relay 750, at the same time opening the circuit of relay 725 at the normally closed contacts controlled by armature 750. Also relay 724 applies booster battery at armature 751 to the release trunk conductor 782 through resistance 734, armature 752 and its working contact, armature 751 and its working contact, and the normally closed contacts controlled by armature 761. The meter associated with the calling subscriber's line is now operated in the usual manner.

A moment later, relay 725 deenergizes and disconnects booster battery from the release trunk conductor 782 at the same time replacing ground thereon.

When the conversation which follows the establishment of the connection is terminated, the two subscribers replace their receivers. Assuming that the called subscriber replaces his receiver first, relays 727 and 728 merely deenergize and no particular result is obtained at this time, except that the supervisory lamp 737 is again lighted at armature 756 and through the normally open contacts controlled by armature 751.

When the receiver is replaced at the calling substation, line relay 733 deenergizes and opens the circuit of release relay 723 at armature 746. Release relay 723 accordingly deenergizes after an interval; opens the circuit of relay 724 at armature 748; removes ground from the locking conductor 784 and from release trunk conductor 782 at armature 747; and at armature 749 closes a circuit through off normal contacts 731 for release magnet 732. Release magnet 732 now energizes and restores the switch to normal in the usual manner. The line switch LS² is released and relay 730 of the first selector repeater deenergizes when ground is removed from the release trunk conductor.

In case the subscriber at substation A² desires to call the subscriber at substation A³, he calls a special number, extending a connection by way of the first selector repeater, Fig. 8, the intermediate selector, and the reverting call switch, Fig. 5, to the ring-back equipment. In this case, as before, battery is momentarily connected to the re-

lease trunk conductor of the established connection through the low wound relay 414, Fig. 5. This results in the energization of the marginal switch-through relay 721, Fig. 8, the lower winding of which is supplying ground to the release trunk conductor. Upon energizing, the switch-through relay 721 closes a locking circuit for its upper winding at armature 742 and at armatures 741 and 744 switches the conductors 781 and 783 through to the wipers, at the same time disconnecting the front and back bridges. The line and release relays 722 and 723 now deenergize, but the connection is held up by ground supplied to the release trunk conductor at the reverting call switch and the first selector repeater is prevented from releasing because the circuit of release magnet 732 is maintained open at armature 743. This connection is released in the same manner as the similar connection established by the subscriber at substation A.

It may be well to mention now that, in view of the slightly different conditions under which it operates, it has been deemed sufficient to provide the first selector repeater of Fig. 8 with only one supervisory lamp instead of the two supervisory lamps provided for the first selector repeater of Fig. 1. It will be remembered that a circuit is closed for the supervisory lamp 737 at armature 760 of relay 729 when the switch is first seized. This circuit remains closed until the switch-over operation takes place and the lamp 737 is extinguished when relay 729 falls back. When the called subscriber answers, it will be remembered that relay 728 closes a circuit for relay 724 which energizes and prepares a circuit for the lamp 737 at the normally open contacts controlled by armature 751. Accordingly, in case the called subscriber hangs his receiver up first, relay 727 deenergizes and completes a circuit for the supervisory lamp at armature 756. On the other hand, on a call that may be extended to an operator's position if the calling subscriber replaces his receiver and the connection is held up by the operator, who, for this purpose applies battery to the lower talking conductor, relay 727 is energized and completes a circuit for the supervisory lamp at armature 756 and its working contact. This circuit includes the resting contact and armature 743, armature 746 and its resting contact, when line relay 722 deenergizes, and armature 749 and its working contact. Release relay 723 is maintained energized at this time from the local locking conductor 784, over a circuit which includes armature 758 and its resting contact and armature 757 and its working contact. The switch is released and the supervisory lamp is extinguished as soon as the

operator removes battery from the local talking conductor.

In order to enable it to be understood how the present system is arranged to operate economically in connection with directors, Fig. 9 should be substituted for Fig. 1 in the layout shown in Fig. 11, and Fig. 10 should be placed below Fig. 9. The first selector repeater shown in Fig. 9 is very similar to the first selector repeater shown in Fig. 1, in that the talking condensers are normally connected between the front and back bridges. Some of the main differences between the two selectors are that the line relay of the switch shown in Fig. 9 does not operate the associated vertical magnet directly but first operates the vertical magnet of the director selector, Fig. 10, and then the various operating magnets of the director and that the sending mechanism of the director controls the vertical magnet of the selector through a repeating relay and controls the setting up of the remaining part of the connection independent of the repeating relay in the first selector repeater after the said switch has been operated.

Another difference between the first selector of Fig. 9 and that of Fig. 1 is that the meter of the calling subscriber's line is operated over a fourth conductor rather than by means of booster battery applied to the release trunk conductor.

In order to enable the operation of the equipment to be understood best, it will be assumed that the subscriber at substation A⁴ desires to converse with the subscriber at substation B, Fig. 4. It will be assumed further that when the subscriber at substation A⁴ removes his receiver, the associated line switch LS³ seizes the associated first selector repeater shown in the drawing. When this occurs, line relay 812 energizes over the calling line and closes a circuit for release relay 813 at armature 846. Release relay 813 thereupon energizes and grounds the release trunk conductor 831 at armature 847 through the low resistance lower winding of the marginally adjusted switch-through relay 811, thereby closing the usual holding circuit for the line switch LS³. As a further result of its energization, relay 813 prepares a circuit for rotary magnet 827 at armature 848 and at armature 849 opens a point in the circuit of release magnet 823 and prepares the operating circuit. As a result of the ground potential being placed upon release trunk conductor 831, relay 818 energizes and closes at armature 855 a circuit through the resting contact and armature 850, armature 853 and its resting contact, and armature 855 for the supervisory lamp 892, and at armature 860 connects conductor 893 to the lower talking conductor through the resting contact and arma-

ture 820. The dial tone source shown in Fig. 10 is connected to the lower talking conductor through the resting contact and armature 925 of switching relay 903 of the director selector. Accordingly, the dial tone is transmitted back to the calling subscriber to inform him that he may start dialling.

When the calling subscriber dials the first digit, line relay 812 of the first selector repeater is deenergized a corresponding number of times and, upon each deenergization, an impulse of current is transmitted to vertical magnet 908 of the director selector, Fig. 10, over the following circuit: from ground by way of the resting contact and armature 843, armature 846 and its resting contact, armature 849 and its working contact, resting contact and armature 967, 20 armature 924 and its resting contact, series relay 902, and vertical magnet 908 to battery. By the operation of vertical magnet 908, the wipers 930-933, inclusive, of the director selector are raised opposite the desired level 25 of bank contacts. Relay 902 is energized in series with vertical magnet 908 upon the first impulse of current being delivered to the latter and, being slow acting, maintains its armature attracted throughout the vertical movement. Upon energizing, relay 702 30 closes at armature 893 a point in the circuit of stepping relay 901 which is completed at off normal contacts 905 when the latter contacts close as they do upon the first vertical step of the switch. This circuit of relay 901 includes the grounded conductor 896 which is grounded at the first selector repeater through the resting contact and armature 867 and armature 848 and its working contact. Upon energizing, relay 901 35 prepares a circuit for rotary magnet 904 at armature 922 and at armature 921 completes a locking circuit for itself which includes the interrupter contacts 911 of the rotary magnet 904.

At the end of the vertical movement of the switch, relay 902 deenergizes and completes the circuit of the rotary magnet 904, whereupon rotary magnet 904 energizes and 40 advances the wipers into engagement with the first set of bank contacts in the selected level. From this point on, the trunk selecting operation is the same as has been described hereinbefore. It will suffice to 45 say that the rotary movement continues until an idle director is found, which director, it will be assumed, is the one shown in the drawings and reached over conductors 934-937, inclusive. When an idle director is 50 reached, switching relay 903 energizes in series with stepping relay 901; opens the test circuit and grounds the test wiper 931 at armature 926; disconnects dial tone from the talking circuit at armature 925; grounds 55 the discriminating conductor 936 at armature

927; opens a point in the circuit of release magnet 907 at armature 928; closes the sending circuit at armature 929; and at armature 924 disconnects the operating conductor 895 from series relay 902 and vertical magnet 908 and connects it through wiper 930 to the operating conductor 934. In the director, the discriminating relay 941 now energizes over conductor 936 and the release relay 940 energizes over conductor 75 935, which is connected to the grounded conductor 896 at armature 926. Relay 940 opens the release circuit to prevent the release of the various switches of the director until the proper time arrives.

In the first selector repeater, relay 819 now energizes over the following circuit: from ground by way of the lower winding of relay 819, normally closed contacts controlled by armature 812, control conductor 897, armature 929 and its working contact, wiper 933, conductor 937, armature of sending relay 938 and its resting contact, and the resistance 942 to battery. Upon energizing, relay 819 closes at armature 862 a circuit through the normally closed contacts controlled by off normal spring 825 for relay 816. This circuit, it may be pointed out, starts at the grounded contact of armature 848 and includes the armature 867 and its resting contact and the resting contact and armature 875. Relay 816 now energizes and prepares a circuit for vertical magnet 826 at armature 856 and at armature 854 prepares a circuit for stepping relay 100 817.

When the calling subscriber dials the next digit in the desired number, line relay 812 is deenergized a number of times and, upon each deenergization, places ground upon the operating circuit extending to the director selector, as previously traced over conductor 895. Each time ground is placed on conductor 895, it is extended through armature 924 and its working contact, wiper 930, and conductor 934 to the operating circuit of the director, resulting in the digit being registered in the usual manner.

In the same way, responsive to the dialling of the remaining digits in the desired number, the impulses representing these digits are transmitted to the operating circuit of the director.

At the proper time, the sending mechanism of the director is started and the sending relay 938 interrupts the outgoing control circuit in accordance with the first digit to be transmitted. Upon each opening of the control circuit for the first digit, relay 818 in the first selector repeater deenergizes and closes at armature 862 a circuit through the working contact and armature 856 of relay 816 and armature 868 and its resting contact for vertical magnet 826. By the operation of vertical magnet 826, the wipers 115 120 125 130

- 878-881, inclusive, are raised opposite the desired level of bank contacts. Upon the first vertical step of the switch, the off normal springs are operated and the circuit of stepping relay 817 is completed at off normal contacts 894 as follows: from ground by way of the working contact and armature 848, working contact and armature 854, armature 874 and its resting contact, off normal contacts 824, and stepping relay 817 to battery. Upon energizing, relay 817 prepares a circuit for rotary magnet 827 at armature 857, and at armature 858 locks itself to ground through the resting contact and armature 871.
- As a further result of the operation of the off normal springs, off normal spring 825 connects relay 816 to the resting contact of armature 862, of relay 819 at the same time disconnecting the said relay 816 from the working contact of armature 862. Accordingly, relay 816 remains energized throughout the series of deenergizations of relay 819 and falls back at the end.
- Upon falling back, relay 816 closes at the normally closed contacts controlled by armature 854 a circuit through armature 853 and its working contact for rotary magnet 827. Rotary magnet 827 thereupon energizes and advances the switch wipers into engagement with the first set of bank contacts in the selected level, at the same time opening the circuit of stepping relay 817 at the interrupter contacts 828. The remaining portion of the trunk hunting operation is the same as has been described hereinbefore. This operation continues until an idle trunk is found, which trunk, it will be assumed, is the one comprising conductors 92-94, inclusive.
- When this trunk is reached, relay 821 energizes in series with stepping relay 817. Upon energizing, relay 821 disconnects ground from armature 862 of relay 819 at armature 875; closes a locking circuit for relay 819 at armature 871 through armature 865 and its resting contact and armature 861 and its working contact; and at armatures 822 and 878 connects up the line wipers 879 and 881, at the same time opening the circuit of the lower winding of relay 819 at the normally closed contacts controlled by armature 872. Battery from the outgoing control conductor 897 is now on the upper wiper 879 and ground is connected to the lower wiper 881 through the normally closed contacts controlled by armature 870. Accordingly, the line relay of the incoming selector repeater, Fig. 2, energizes with the results hereinbefore pointed out.
- It may be mentioned at this time that when directors are employed the inter-office trunking arrangement is usually modified, and the practice of direct trunking from the calling office to the called office is abandoned for the more economical arrangement from a trunking standpoint of reaching the called office through one or more intermediate offices when the called office is remote. However, in the present case it may be assumed that the called office is near the calling office, in which case it is reached direct as explained above.
- The incoming selector repeater responds to the second digit transmitted by the sender and operates in the hereinbefore described manner and, responsive to each of the remaining digits, rotates as hereinbefore described with the final result that the connection is extended to the line of substation B through an intermediate selector and a connector, the ones shown in Figs. 3 and 4 for example.
- When the connector lands upon the called line its line relay is cut off in the usual manner and the usual switch-over operation takes place in the incoming selector repeater. However, no switch-over operation takes place at the first selector repeater responsive to the revertive control from the incoming selector repeater, but the switch-over operation is controlled from the director, as will now be explained.
- In the director, Fig. 10, when the last digit has been transmitted, switching relay 939 energizes and places ground on the switching conductor 934 thereby closing a circuit through wiper 930, working contact and armature 924, and conductor 895 for switching relay 820 of the first selector repeater. Relay 820 now energizes and closes a locking circuit for itself at armature 866, and at armatures 864 and 870 completes the talking circuit, at the same time disconnecting the outgoing control conductor 897 from the upper wiper 879 and disconnecting ground from the lower wiper 881. As a further result of the energization of switching relay 820, it places ground on release conductor 894 at armature 869, and at armature 867 removes ground from conductor 896, whereupon switching relay 903 of the director selector deenergizes and disconnects its wipers, and at the same time closes at armature 928 a circuit for release magnet 907 as follows: from ground by way of working contact and armature 869 of relay 820, Fig. 9, conductor 894, resting contact and armature 928, off normal contacts 906, and release magnet 907 to battery. The director selector is now restored to normal in the usual manner, whereupon the circuit of release magnet 907 is opened at off normal contacts 906.
- The director is restored to its normal condition responsive to the deenergization of release relay 940, which occurs when ground is removed from wiper 931 at armature 926.
- As a still further result of the energization of switching relay 820 of the first selector repeater, the locking circuit of relay 819

is opened at armature 865, whereupon relay 819 deenergizes and connects up relays 814 and 815 at armatures 861 and 863, respectively.

5 When the called subscriber answers, the incoming selector repeater, Fig. 2, cuts the resistance 115 out of its front bridge, whereupon relays 814 and 815, Fig. 9, energize and relay 814 completes at armature 851 the following circuit for relay 816: from ground by way of the working contact and armature 848 of relay 813, resistance 829, working contact and armature 868, armature 851 and its working contact, off normal spring 825 and its contact, and relay 816 to battery. Upon energizing, relay 816 shunts armature 851 and its working contact at armature 856, thereby closing a locking circuit for itself independent of relay 814, and at 20 armature 854 places ground upon the meter operating conductor 833 through armature 874 and its working contact, thereby operating the meter individual to the calling line.

When the called subscriber hangs up his receiver after the conversation is terminated, relays 814 and 815 deenergize, but no particular result is produced at this time.

When the calling subscriber replaces his receiver line relay 812 deenergizes and opens the circuit of relay 813 at armature 846, and relay 813 energizes after the interval for which it is adjusted, opening the circuits of the various locked up relays at armatures 847 and 848, and closing a circuit for release magnet 822 at armature 849 through off normal contacts 823. The switch is now released in the usual manner and the remaining part of the connection is released in the manner described hereinbefore.

40 Although the talking condensers are not normally connected to the wipers 879 and 881 of this first selector repeater during the setting up of a connection, as is the case with the first selector repeater, Fig. 1, this first selector repeater may be used to complete connections to an ordinary two-wire office through an incoming selector repeater of the type shown in Fig. 6 because the director operates the switching relay 820, as hereinbefore described, when the last digit is transmitted, thereby enabling any busy tone or other tone to reach the calling subscriber.

55 This selector repeater may also be used in cases where it is desirable to switch the connection straight through without any talking condensers or bridges. For example, if a connection is extended to the ring-back equipment through the intermediate selector and reverting call switch of Fig. 5, the various relays of the reverting call switch operate in the manner hereinbefore described to place battery through a low resistance relay on the release trunk conductor of the established connection when the calling sub-

scriber hangs up his receiver after having dialled the special number. In this connection, it may be noted that the battery to wiper 879 is opened at armature 845 of line relay 812 when the calling subscriber hangs up so as to bring about the above mentioned operations in the reverting call switch.

In the first selector repeater, the marginal switching through relay 811 responds to the application of battery through the low resistance to the release trunk conductor by energizing. Upon energizing, relay 811 closes a locking circuit for its upper winding at armature 842, opens up the release circuit of the switch at armature 843, and at armatures 841 and 844 switches the connection through and cuts off both bridges. This connection is released in the manner described hereinbefore in connection with the first selector repeater of Fig. 1.

It may be well to point out at this time the manner in which the supervisory lamps 891 and 892 are operated. When ground is placed upon the release trunk conductor 831, upon the switch being first seized, relay 818 energizes as described hereinbefore and closes at armature 855 a circuit through the resting contact and armature 850, armature 853 and its resting contact, and armature 855 and its resting contact for the lamp 90 892, which becomes lighted and remains lighted until relay 816 energizes, during the vertical movement, and lights up again when relay 816 falls back after the vertical movement is terminated. The lamp then remains lit until relays 814 and 815 energize when the called man answers. Also, it will be remembered that relay 816 energizes at this time and remains locked up until the connection is released. Accordingly, after the 105 called man hangs up and before the calling man hangs up, a circuit is closed through armatures 850 and 853 and through armature 855 and its working contact for the lamp 891, which lights up to indicate that 110 the calling man is holding the connection after the called man has hung up.

In case a connection is extended through this first selector repeater to an operator's position, the operator may hold up the first 115 selector repeater by applying battery to the lower talking conductor, thereby energizing relay 815. This closes a circuit through the resting contact and armature 850 and armature 853 and its working contact for release relay 813.

In case the director selector, Fig. 10, is unable to find an idle director, it rotates off the last bank contacts and closes the eleventh rotary step contacts thereby connecting the 125 common busy tone lead 910 to conductor 93' which is connected to the lower talking condenser through the working contact and armature 860, resting contact and armature 870, and armature 844 and its resting con- 130

tact. Accordingly, the busy tone is transmitted back to the calling subscriber in the usual manner. The same thing happens in case the first selector repeater is unable to 5 find an idle trunk.

Attention will now be called to the two-way trunk line, Fig. 2. This trunk line, it will be noted, is accessible from both ends and has an incoming selector repeater on 10 both ends. It has been pointed out hereinbefore how release relay 103 of the incoming selector repeater shown in the drawing makes the trunk line busy in the banks of the local switches when it is seized from the 15 opposite end. Now, when the trunk line TL is seized at the multiple extending above the incoming selector repeater shown, cut off relay 101 is energized through armature 125 and its resting contact and disconnects the 20 talking conductors of the trunk line from the local incoming selector repeater.

What is claimed is:

1. In a telephone system, means including a selector repeater and a final connector 25 for connecting a calling and a called line, a control circuit extending between said switches, means in said selector repeater for supplying current to said control circuit and for interrupting the current supply to transmit 30 digit impulses, and a relay in said connector responsive to such impulses for setting the connector on a called line.

2. In a telephone system, means including a selector repeater and a final connector for 35 connecting a calling and a called line, a control circuit extending between said switches, means in said selector repeater for supplying current to said control circuit and for interrupting the current supply to transmit 40 digit impulses, a relay in said connector responsive to such impulses for setting the connector on a called line, and means for altering the control circuit at said connector to supply talking current to the called 45 station.

3. In a telephone system, means including a selector repeater and a final connector for connecting a calling and a called line, a control circuit extending between said switches, 50 means in said selector repeater for supplying current to said control circuit and for interrupting the current supply to transmit digit impulses, a relay in said connector responsive to such impulses for setting the connector on a called line, and means responsive to the completion of the connection for disconnecting the conductors of said control circuit from said connector relay and for connecting them to the conductors of the called line to supply the called station with talking current.

4. In a telephone system, automatic switches of the type in which the line relay is bridged across the line independent of 60 the battery, a selector repeater for control-

ling such switches, said selector repeater having a repeating bridge including a battery, other automatic switches of the type in which the line relay is bridged across the line in series with a battery, a second selector repeater intervening between said first mentioned selector repeater and said other switches, and line relay and repeating bridges in said second selector repeater both excluding the battery. 70 75

5. In a telephone system, means including a repeater and a final connector for connecting a calling and a called line, a control circuit extending between said repeater and said connector, means in said repeater for supplying a steady flow of current to said control circuit and for interrupting the current supply at any time thereafter to transmit digit impulses, and a relay in said connector responsive to such impulses for 80 85 setting the connector on a called line.

6. In a telephone system, means including a repeater and a final connector for connecting a calling and a called line, a control circuit extending between said repeater and said connector, means in said repeater for supplying current to said control circuit and for interrupting the current supply to transmit digit impulses, a relay in said connector responsive to such impulses for 90 95 setting the connector on a called line, and means for altering the control circuit at said connector to supply talking current to the called station.

7. In a telephone system, means including a repeater and a final connector for connecting a calling and a called line, a control circuit extending between said repeater and said connector, means in said repeater for supplying current to said control circuit and for interrupting the current supply to transmit digit impulses, a relay in said connector responsive to such impulses for setting the connector on a called line, and means responsive to the completion of 100 105 the connection for disconnecting the conductors of said control circuit from said connector relay and for connecting them to the conductors of the called line to supply the called station with talking current. 110 115

8. In a telephone system, automatic switches of the type in which the line relay is bridged across the line independent of the battery, a repeater for controlling such switches, said repeater having a repeating bridge including a battery, other automatic switches of the type in which the line relay is bridged across the line in series with a battery, a second repeater intervening between said first mentioned repeater and said other switches, and line relay and repeating bridges in said second repeater both excluding the battery. 120 125

9. In a telephone system, an automatic impulse repeater, automatic switching 130

- mechanism controlled by said repeater to set up a connection from a calling line to any one of a plurality of called lines, and means associated with a certain one of said 5 called lines for cutting out said repeater responsive to the extension of the connection to said line.
10. In a telephone system, an automatic impulse repeater, automatic switching mechanism controlled by said repeater to set up a connection including said repeater and extending to a called line, and means responsive to the extension of the connection to said line for cutting out said repeater.
15. 11. In a telephone system, a trunk line, a bridge across said trunk line, a circuit including said bridge and trunk line, automatic switching mechanism controlled over said circuit to extend a connection therefrom to a called line, and means responsive to the extension of said connection to said line and controlled over the conductors thereof for removing said bridge from across said trunk line.
20. 12. In a telephone system, a trunk line divided into two sections, automatic switching mechanism controlled over the second section of said trunk line to extend a connection therefrom to a called line, and means responsive to the extension of said connection to said called line for uniting the two sections of said trunk line.
25. 13. In a telephone system, a trunk line divided into two sections, a bridge across one of said sections, automatic switching mechanism controlled over the second section at said trunk line to extend a connection therefrom to a called line, and means responsive to the extension of said connection to said 30 called line for uniting the two sections of said trunk line and for removing said bridge from across the associated section.
35. 14. In a telephone system, a trunk line divided into two sections, two bridges across said sections, respectively, automatic switching mechanism controlled over the second section of said trunk line to extend a connection therefrom to a called line, and means responsive to the extension of the connection to the called line for removing both of said 40 bridges from across the sections of said trunk line and for uniting the two sections together.
45. 15. In a telephone system, a trunk line divided into two sections, automatic switching mechanism, means for operating said mechanism to set up a connection from a calling line to a called line including said trunk line, connections for supplying talking current to the calling line over one section of said trunk line and for supplying talking current to the called line over the other section on said trunk line, a reverting call device, means including said switching mechanism for setting up a connection from a 50 station on a calling party line to said device including the two sections of said trunk line in serial relation, means associated with said device for signaling a called station on the calling line, and means for supplying talking current to the calling and called stations on said line from said device and through the two sections of said trunk line in series.
55. 16. In a telephone system, a trunk line divided into two sections, a closed circuit including the first section of said trunk line and a current source, a closed circuit including the second section of said trunk line and a current source, an automatic impulse repeater at the junction of said sections responsive to interruptions in the first closed circuit to produce interruptions in the second closed circuit, automatic switching mechanism responsive to the interruptions produced in the second closed circuit to extend a connection from the second section of said trunk line to a called line, means for reversing the direction of the current flow in the second closed circuit responsive to the answering of the subscriber at the called station, and means responsive to such reversal for momentarily reducing the current flow in the first closed circuit and for then reestablishing the current flow again in the 60 original direction.
65. 17. In a telephone system, a trunk line divided into two sections, a closed circuit including the first section of said trunk line and a current source, a closed circuit including the second section of said trunk line and a current source, an automatic impulse repeater at the junction of said sections responsive to interruptions in the first closed circuit to produce interruptions in the second closed circuit, automatic switching mechanism responsive to the interruptions produced in the second closed circuit to extend a connection from the second section of said trunk line to a called line, means for reversing the direction of the current flow in the second 70 closed circuit responsive to the answering of the subscriber at the called station, means responsive to such reversal for momentarily reducing the current flow in the first closed circuit, and means responsive to a restoration of the current flow in the second section to the original direction for reducing the current flow in the first section and for maintaining it reduced as long as the current flow in the second section remains in its 75 original direction.
80. 18. In a telephone system, a trunk line, a train of automatic switches for setting up a connection from said trunk line to a called line, means for transmitting impulse series to operate said switches to set up said connection, a battery feed bridge at said trunk line for supplying talking current to the called line, means for connecting said battery feed bridge to said trunk line after 85
90. 95. 100. 105. 110. 115. 120. 125. 130.

- the last of said impulses has been transmitted, and means associated with said trunk line for preventing said battery feed bridge from being connected to said trunk line in 5 case one or more of said switches has failed to respond properly.
19. In a telephone system, a trunk line, an impulse sender for transmitting series of impulses over said trunk line, a train 10 of automatic switches responsive to said impulses to extend a connection from said trunk line to a called line, a supervisory device associated with said trunk line, means for placing said device under the control 15 of the called line after all the impulses have been transmitted, and means for preventing said device from being so placed under the control of said called line in case one or more of said switches has failed to respond 20 properly.
20. In a telephone system, a trunk line, means for sending series of impulses over said trunk line, a train of automatic switches responsive to said impulses to extend a 25 connection from said trunk line to a called line, a switch-over relay, means for operating said switch-over relay after all of said impulses have been transmitted, a test relay energized in a local circuit prior to the said 30 operation of said switch-over relay, contacts on said switch-over relay for opening said local circuit and for connecting said test relay to said trunk line, circuit connection for maintaining said test relay energized in case 35 one or more of said automatic switches has failed to operate properly, a battery feed bridge for said trunk line, and circuit connections for disconnecting said test relay from said trunk line and for substituting 40 said battery feed bridge in case said test relay does not remain energized after the operation of said switch-over relay.
21. In a telephone system, a train of automatic switches including a selector repeater, 45 a director including registering and sending equipment, a line relay in said selector repeater responsive to current impulses received over a calling line to transmit impulses to set the registering equipment in 50 said director, an impulse conductor, means for operating the sending equipment of said director in accordance with the instant setting of the associated registering equipment to transmit a series of impulses over said 55 impulse conductor to said selector repeater, a repeating relay in said selector repeater responsive to said series of impulses to operate said selector repeater, a switching relay in said selector repeater operated at the 60 end of the operation of said selector repeater to extend the connection to the next switch in the train, and contacts on said relay for disconnecting said impulse conductor from said repeating relay and for extending it 65 directly to the seized trunk line.
22. In a telephone system, a trunk line leading to an automatic switch, a line relay and a combined change-over and release relay for said switch, said trunk line comprising a pair of talking conductors and a holding conductor, means for energizing 70 said line relay over one of said talking conductors and for energizing said combined release and change-over relay over said holding conductor, means for deenergizing said line relay a number of times to operate said switch, a circuit for deenergizing said combined release and change-over relay closed on each energization of said line relay following the first deenergization, whereby said 75 combined change-over and release relay is maintained energized throughout the series of deenergizations of the line relay but is deenergized a moment after said series is terminated, and means for deenergizing said 80 combined release and change-over relay immediately by removing the holding potential from said holding conductor prior to the regular operation of said switch.
23. In an automatic switch employing a 85 combined release and change-over relay energized upon the seizure of the switch and maintained energized until the directive operation of the switch is terminated, an externally controlled circuit for said relay closed 90 upon the seizure of the switch, and means for intermittently shunting said relay during the directive operation of said switch, whereby the deenergization of said relay is secured when it is shunted continuously at 95 the end of the directive operation of the switch.
24. In an automatic switch employing a 100 combined release and change-over relay energized upon the seizure of the switch and maintained energized until the directive operation of the switch has been effected, an external circuit for said relay for effecting the energization of the same when the switch is seized, means for opening said external 105 circuit to secure a quick deenergization of said relay, and means in the switch for shunting said relay for securing a slow deenergization of the relay to permit it to remain energized while its circuit is intermittently 110 shunted during the directive operation of the switch.
25. In a telephone system, an automatic switch having a release trunk conductor grounded at a point outside the switch, an operating magnet for said switch, a release magnet for said switch, a release relay for 115 said switch energized over said release trunk conductor, a local conductor included in the said circuit of said release relay, means for deenergizing said release relay by removing said external ground connection from the said release trunk conductor, contact on said release relay operated when it deenergizes to 120 disconnect said local conductor from itself.

- and to connect it to said release magnet instead, other contacts on said release relay for disconnecting said local conductor from said release trunk conductor and for connecting it to a local source of ground potential to energize said release magnet, and a circuit for said operating magnet including other contacts on said line relay and other contacts on said release relay.
26. In a telephone system, a trunk line, means for seizing said trunk line, a supervisory signal individual to said trunk line operated subsequent to said seizure, a train of automatic switches and means for operating them over said trunk line to extend a connection from said trunk line to a called line, and means for restoring said signal only after all of said switches have been operated.
27. In a telephone system, a trunk line, means for seizing said trunk line, a supervisory signal individual to said trunk line operated subsequent to said seizure, a train of automatic switches and means for operating them over said trunk line to extend a connection from said trunk line to a called line, means for restoring said signal only after all of said switches have been operated, a relay in said trunk line operated upon the response of the subscriber of the called line, and circuit connections controlled by said relay for operating said signal when the subscriber on the called line hangs up and for maintaining it operated until the release of the established connection takes place.
28. In a telephone system, a trunk line, means for seizing said trunk line, automatic switches controlled over said trunk line subsequent to the seizure thereof to extend a connection from said trunk line to a called line, and means including supervisory means associated with said trunk line for indicating a certain condition in case the trunk line has been seized and all the switches necessary to set up the connection have not completely operated and for indicating a different condition if the connection still remains established after the called subscriber has answered and has again replaced his receiver.
29. In a telephone system, means including a repeater and a final connector for connecting calling and called lines, a control circuit including the two talking conductors in series extending between said repeater and said connector, means in said repeater for supplying current to said control circuit and for interrupting the current supply to transmit digit impulses, and a relay in said connector included in said control circuit responsive to said impulses for setting the connector on a called line.
30. In an automatic telephone system, automatic switches of the type in which the line relay is bridged across the line inde-
- pendent of any current supply or ground connections, and a repeater for controlling such switches, said repeater having a controlling bridge across the talking conductors thereof including a source of current, and means for interrupting the current flow therefrom to operate said switches.
31. In a telephone system, means including a trunk line and a train of automatic switches for setting up a telephone connection, means associated with said trunk line for maintaining said automatic switches operated, means including said trunk line and another train of automatic switches for setting up another connection, and means included in said other connection for causing the holding of the automatic switches to be transferred from said trunk line to another link in the last named connection.
32. In a telephone system, means including a trunk line and a train of automatic switches for setting up a telephone connection, a repeater inserted in the trunk line for controlling said switches to set up the said connection, means in said repeater for closing a circuit to hold the switches operated after they are set, means including said trunk line for setting up a connection including another train of automatic switches, and means controlled from one of the links in the last mentioned connection for closing a new holding circuit for the operated switches and for eliminating said repeater from the connection.
33. In a telephone system, means including a trunk line and a train of automatic switches for setting up a telephone connection, a repeater inserted in the trunk line for controlling said switches to set up the said connection, means in said repeater for closing a circuit to hold the switches operated after they are set, means including said trunk line for setting up a connection including another train of automatic switches, means controlled from one of the links in the last mentioned connection for closing a new holding circuit for the operated switches and for eliminating said repeater from the connection, and means responsive to the elimination of the repeater from the connection for establishing a third holding circuit for the automatic switches.
34. In a telephone system, means including a repeater and a final connector for connecting a calling and a called line, a control circuit extending between said repeater and said connector, circuit connections in said repeater for supplying current to said control circuit, means for closing said control circuit to set up a current flow thereover, and separate means in said repeater for interrupting said circuit to send digit impulses thereover, and a relay in said connector responsive to such impulses to set said connector on a called line.
35. In a telephone system, means including

a repeater and a final connector for setting up telephone connections, a control circuit extending from said repeater to said connector, circuit connections in said repeater for supplying current to said control circuit until said connector is set, means in said repeater for interrupting the current flow over said control circuit to transmit digit impulses, and a relay in said connector responsive to such impulses to set the connector on a called line.

36. In a telephone system, means including a repeater and an automatic switch for extending a connection to a telephone line, a control circuit extending between said repeater and said switch, means in said repeater for supplying current to said control circuit for setting said switch, and means for altering the control circuit at said switch to enable talking current to be supplied to the station upon said telephone line from said repeater.

37. In a telephone system wherein automatic switching apparatus is controlled from

a repeater over a control circuit to set up a connection to a telephone line, circuit connections in said repeater for supplying the current used in said control circuit while the connection is being set up and for supplying talking current to said line after the connection is set up thereto.

38. In a telephone system, means including a controlling device and an automatic switch for setting up a telephone connection, a control circuit including the two talking conductors in series extending between said control device and said switch, circuit connections in said control device for supplying current to said control circuit and for altering the current supplied to said control circuit to transmit digit impulses, and means included in said switch for setting the switch in accordance with said digit impulses.

In witness whereof, I hereunto subscribe my name this 17th day of May, A. D. 1924.

JOHN WICKS.
